UNITED STATES PATENT OFFICE.

GERHARDT F. SCHWARTZ, OF ST. LOUIS, MISSOURI.

METHOD OF MAKING HOT-WATER TANKS.

Application filed November 11, 1922. Serial No. 600,481.

The present invention relates to improvements in hot water tank construction and methods for constructing such tanks in which economy and strength are sought to be secured.

Now in the present construction of hot water tanks, both the cylindrical body and the tops and bottoms, or heads, are made of sheet copper, which is relatively thin and malleable and therefore not possessed of any considerable strength but supplying the desired qualities of high conductivity to permit of a ready transference of heat through the tank walls and a proper resistance to the direct application of heat to avoid the burning out of parts of the tank and to the deteriorating effects of heated water.

Because of this thinness and malleability in the sheet copper, it has always presented considerable of a problem to boiler makers and coppersmiths to adequately and effectively secure to the tank the water pipes. Due to its malleability and the thin character of sheet copper, it has been found impracticable to secure the water pipes directly in this material and resort must be had to the placement of fittings or spuds in the copper heads or walls of the tank to receive the pipes, and of course the copper must be carefully and skillfully operated upon at great cost of coppersmith labor to receive fittings which are necessarily expensive. The copper itself of which the heads are made is at a very high figure in the market and altogether, the labor, and cost of the heads and the fittings so increase the cost of production of hot water tanks that it has become a most perplexing problem to manufacturers of such devices to be able to produce and market them, particularly under prevailing market conditions, at an adequate profit.

It is an object of the present invention to deal with this situation by dispensing entirely with any labor upon hot water tank construction heretofore required of the coppersmith; secondly to reduce the cost of the material of which tank heads are made and at the same time to replace this copper sheet material by a casting, which is also a cheaper variety and combined with the cheapness in the material itself and the inexpensiveness of producing a cast article as against a sheet metal article to thus materially reduce the cost of this item; and thirdly to dispense entirely with the cost

of fittings by enabling the castings or heads to directly receive the water pipes and to so construct these cast heads as to enable them to perform this office.

With the foregoing and other objects in view, the invention will be more fully described hereinafter, and will be more particularly pointed out in the claims appended hereto.

In the drawings, wherein like symbols refer to like or corresponding parts through the several views:

Figure 1 is a vertical sectional view of a hot water tank constructed according to the present invention.

Figure 2 is a top plan view of the same.

Figure 3 is a fragmentary section of the lower portion of a hot water tank showing a slight modification.

Figure 4 is an edge view of the bottom head, and

Figure 5 is a fragmentary enlarged section through the joint between the bottom head and the sheet metal body.

Referring more particularly to the drawings, 1 designates the sheet copper body of which hot water tanks are customarily made. The body is tubular and generally cylindrical with open ends which are according to the present custom closed by heads also of sheet copper.

However according to the invention I dispose with the relatively thin malleable copper heads and in their place I substitute a head thicker in construction, made from a material possessing the same qualities of high conductivity and resistance to heat and water action and which is of a character and thickness suitable to provide therein openings to receive the water pipes and to firmly hold these pipes in place in leak-tight fashion without the likelihood of the pipes tearing out of the heads which is a source of much annoyance and expense with the sheet copper construction.

The top head 2 and the bottom head 3 are both made from brass or phosphor bronze as this material possesses the necessary conductivity and resistance to heat. The heads are cast which is permissible by the material used and this greatly reduces the expense as compared with the sheet metal article. Moreover the casting enables the provision of greater thickness in the heads as compared with the sheet metal heads and this inures to a better construc-

tion by reason of the fact that suitable depth is afforded for the drilling of openings 4 and 5. These openings are also machined and are an integral part of the brass or phosphor bronze heads and they receive the water pipes directly and they present the necessary area against faces of the water pipes to properly support them, while at the same time the rigid and hard character of the brass or phosphor bronze avoids any tendency of the pipes to tear through the heads.

The outer head 2 is provided with a depending marginal flange 6 which is of a diameter to snugly fit within the upper open end of the cylindrical copper body 1. The body is sweated and shrunk on or brazed to the flange these being thereafter riveted as indicated at 7 and sealed with suitable luting, if desired this connection can also be brazed. In the instance shown a center flue 8 passes up through the upper head 2, the head being provided with an upwardly directed flange 9 fitting tightly against the flue and being secured thereto if desired in any feasible manner, brazing, sweating or riveted.

The lower head 3 or bottom is also provided with a downwardly turned flange 10 fitting in the lower end of the body 1 and being sweated therein and having the rivets 11 passed through the two thicknesses. An upwardly directed flange 12 fits against the wider portion 13 of the flue and is brazed, riveted or otherwise secured thereto. In this instance a half size head 14 is required to connect the portions 8 and 13 of the flue and if desired this head may be also of cast brass or phosphor bronze. Rivets 15 and 16 or other suitable fastenings are employed to secure this intermediate head with the flue parts.

Now in Figures 3 and 4 a slight modification is shown in which lugs 17 are produced above the flange 10 of the bottom head 3 in position to lie snugly against the inner face of the cylindrical body adjacent the bottom of the tank. The lug is drilled, machined and threaded as indicated at 18 and the copper of the body is punctured as at 19 to register with the opening 18. In this case the connection of the water pipes is made through the side wall of the tank rather than through the heads and by the provision of the lug 17, a firm support for the pipes is provided thus avoiding the tearing out of the opening 19 in the copper and

the need of expensive fittings within the opening 19 and also with the excessive cost of coppersmith work in mounting these 60 fittings in place.

Now in Figure 5 is indicated an enlarged view showing to some extent the different characteristics of sheet copper and cast brass or phosphor bronze. The phosphor bronze 65 or brass is of a more rigid mass and the casting of this material results in a porous structure. The copper, being malleable, and particularly under the influence of sweating, will enter the pores and interstices 70 of the head flange and it is also preferred to place the copper under pressure to force it intimately into the head structure. Preferably the flange will be machined on its outer face but microscopic pores will still 75 exist and by the sweating and pressing, or brazing under such conditions, of the copper mass the heat will produce a more intimate union between these two.

It will be appreciated from the foregoing 80 that the invention enables me to reduce the cost of manufacture and to eliminate the necessity for putting in special fittings in the openings to receive the water pipes and in general the improvement contributes materially to the production of commercially 85 better hot water tanks.

I have shown and described a preferred 90 and satisfactory construction and in connection therewith have detailed the steps of the process but various changes and modifications could of course be made and I reserve the right to all changes and modifications as may come fairly within the scope of the following claim:

What is claimed:

That method of constructing hot water tanks which consists in making a sheet metal body part with open ends, casting copper alloy rigid heads and fitting the same in the 100 open ends of said sheet metal body part to brace and strengthen the same, sweating the ends of the body part onto said rigid heads to seal the heads therein, riveting the heads to the body part to reinforce the connection 105 between the heads and the body part, and making threaded openings through said rigid cast heads to directly receive pipes leading to and from the tank without the use of spuds and fittings.

In testimony that I claim the foregoing as my invention, I have signed my name hereunder.

GERHARDT F. SCHWARTZ.
